CLAIM

The ornamental design for a combined carry-on, garment bag and toilet kit assembly, substantially as shown and described.

DESCRIPTION

FIG. 1 is a left side elevational view of a combined carry-on, garment bag and toilet kit assembly showing my new design, the right side being a mirror image thereof;

FIG. 2 is a front elevational view, the rear being substantially the same but with strap;

FIG. 3 is a top plan view thereof;

FIG. 4 is a bottom plan view thereof;

FIG. 5 is an exploded perspective view thereof;

FIG. 6 is a top plan view of the garment bag in extended position the other bags removed for convenience of illustration;

FIG. 7 is a bottom plan view thereof, the straps broken away for convenience of illustration;

FIG. 8 is a front elevational view of the carry-on bag, the other bags removed for convenience of illustration; the rear view being a mirror image thereof;

FIG. 9 is a left side elevational view the right side being a mirror image thereof;

FIG. 10 is a bottom plan view thereof;

FIG. 11 is an interior view of the carry-on bag;

FIG. 12 is a bottom plan view of the toilet kit, the other bags removed for convenience of illustration, and FIG. 13 is a top plan view thereof.
